UNITED STATES PATENT OFFICE.

ALFRED R. SWEARINGEN, OF LAKEWOOD, OHIO, ASSIGNOR OF ONE-HALF TO BERNARD C. LIZENBY, OF COLUMBUS, OHIO.

DESIGN FOR A SOUND-REPRODUCING CABINET.

Application filed May 18, 1925. Serial No. 13,483. Term of patent 3½ years.

To all whom it may concern:

Be it known that I, ALFRED R. SWEARINGEN, a citizen of the United States, and a resident of Lakewood, county of Cuyahoga, and State of Ohio, have invented a new, original, and ornamental Design for Sound-Reproducing Cabinets, of which the following is a specification, reference being had to the accompanying drawing, forming part thereof.

In said annexed drawing:—

The single figure there appearing is a perspective view of a sound reproducing cabinet showing my new design.

I claim:—

The ornamental design for a sound reproducing cabinet as shown.

Signed by me, this 16th day of May, 1925.

ALFRED R. SWEARINGEN.
